UNITED STATES PATENT OFFICE.

ALFRED WHITE MORGAN, OF BURLINGTON, IOWA.

TOP-SPINNER.

SPECIFICATION forming part of Letters Patent No. 652,489, dated September 25, 1900.

Application filed May 14, 1900. Serial No. 16,669. (No model.)

To all whom it may concern:

Be it known that I, ALFRED WHITE MORGAN, a citizen of the United States, residing at Burlington, in the county of Des Moines and State 5 of Iowa, have invented a new and useful Top-Spinner, of which the following is a specification.

This invention relates to top-spinners; and the object of the same is to provide simple 10 and effective means for spinning a top without applying the cord directly to the same and wherein the parts are reversible, so that either end of the improved device may be employed to carry out the operation desired, and 15 embodying structural features which will prevent obstructive entanglement or disarrangement of the primary operating device.

The invention consists, essentially, of a holder having a spindle freely slideable there- 20 through and arranged adjacent to a bearing-surface and having a cord or strap, either flat or round, wound thereabout and the coils dis- posed in regular order within the confines of the holder and adapted to contact with said 25 bearing-surface and be thereby prevented from overlapping or becoming entangled and caused to feed outward from and on the said spindle with regularity and uniformity irrespective of the end of the latter used to sup- 30 port the top.

The invention further consists of a holder having a spindle freely rotatable and longitudinally slideable therein and provided with a hollow terminal seat with similarly-extend- 35 ing spiral arms and a top having similarly-ar- ranged spiral grooves adjacent its plug end and means for operating the said spindle.

The invention further consists in the construction, arrangement, and combination of 40 the details, which will be more fully herein-after described and claimed.

In the drawings, Figure 1 is a perspective view of the improved device, showing a top in operative relation thereto and a round cord 45 on the spindle. Fig. 2 is a similar view of the improved device, showing a flat cord on the spindle. Fig. 3 is a horizontal section through the holder and spindle shown by Fig. 1, illustrating the cord on the spindle and the relation of the latter and the cord to the bearing- 50 surface or guard of the holder. Fig. 4 is an enlarged detail perspective view of one of the

terminal seats of the spindle. Fig. 5 is a transverse vertical section through the device shown by Fig. 4. Fig. 6 is an inverted perspective view of the top. Fig. 7 is a sectional view through a portion of the spindle, showing one mode of securing the cord thereto. Fig. 8 is a perspective view of a different form of the improved device, showing a skeleton 60 holder and a different manner of attaching the cord to the spindle. Fig. 9 is a detail sectional view of a portion of the spindle shown by Fig. 1.

Similar numerals of reference are employed 65 to indicate corresponding parts in the several views.

The numeral 1, Figs. 1 and 2, designates a holder, which is preferably of elongated oval form and comprises an outstanding inclosing 70 rim 2 and a continuous slightly-bowed resili- ent back 3, which yields sufficiently to pro- duce an easy contact for a purpose which will be presently set forth. Freely rotatable in and longitudinally movable through the 75 opposite end portions of the rim 2 is a spin- dle 4, having terminal seats 5, (clearly shown in Figs. 4 and 5,) and comprising, primarily, bent wires applied to the ends of the spindle and spirally twisted to form a socket at each 80 end of the latter and the free ends bent out a greater distance than the coils of the sock- ets and spirally bent and projected in the same direction to produce engaging arms 7. The seats loosely receive the plug 8 of the 85 top 9, and the arms 7 loosely bear in spiral grooves 10 in the body of the top adjacent the plug to properly support and whirl the latter simultaneously with the rotation of the spindle. The ends of the arms 7 contact 90 with shoulders 11 at the upper ends of the grooves 10, so that the top will be caused to rotate at the same rate of speed as the spin- dle without lost motion. The wire length 95 employed in forming each seat is firmly se- cured to the spindle by solder or other means. Regularly wound on the spindle within the confines of the holder is an operating-cord 14, the cord shown in Fig. 1 being round and that disclosed by Fig. 2 being flat. The op- 100 posite extremities of the cord extend away from the spindle in reverse directions and have free movement through eyes 15 in the end portions of the holder, the said eyes be-

ing sufficiently large to avoid abrasion and wear on the cord. The flat cord will adhere to the spindle with greater frictional tendency in view of its flat construction than the 5 round cord and need not therefore be secured to said spindle. It is preferred, however, to secure the cord, and particularly the round cord, in order to prevent slipping of the same and any tendency to lost motion and to obtain 10 a positive response to the actuation of the cord. In Fig. 7 the cord is shown threaded through and secured in a transverse opening 16 in the spindle, the said opening being the intermediate limit of the reverse unwinding operations of the opposite cord extremities. In 15 Figs. 8 and 9 the spindle is formed with a groove 17, in which the cord is tied, and other means for securing the cord will be adopted at will.

20 In Fig. 8 the holder 18 is of skeleton form and comprises an elongated oval band 19, having its terminals overlapped, and the opposite end portions of said band are connected by a brace-band 20, extending centrally over 25 one side of the same. The band 19 provides a supporting means or main body of the modified form of the holder, and the ends of the brace-band are bent around the end portions of said band 19 and at one end cover 30 the overlapped terminals of the latter, openings for the spindle being formed through the two engaging parts at each end to thereby produce a reinforced bearing. In other respects the form of the improved device 35 shown by Fig. 8 is similar to the forms heretofore referred to, and the brace-band 20 also provides a frictional bearing or guard of a yielding nature, and the function of the two different forms of bearings or guards as 40 disclosed by the said back 3 and the band 20 is to prevent the coils of the cord on the spindle from overrunning or becoming entangled during the winding or unwinding operation of the same, and the distance between the said 45 spindle and the bearing or frictional structures will be about equal to the thickness of the cord, so that the latter will always have a loose contact with the said structures to prevent the coils from overlapping, yet permit 50 perfect freedom in winding and unwinding without strain or injurious pressure on the said cord. It will also be seen that the frictional structures or guards engage the cord-coils at one point only, which is sufficient to 55 cause the latter to properly climb and bind on the spindle with ample friction to obtain the desired regularity and rapidity of rotation of said spindle and without requiring undue exertion in drawing the cord from the 60 spindle. This particular arrangement of parts and the function of the same are material in view of the fact that the cord will be less liable to break, the operation of the spindle will be forceful with a minimum amount of 65 applied operating power, and the strain on all the parts of the device will be reduced, and

thereby overcome the disadvantages of previously-constructed devices of a similar character, wherein the cord-coils are completely surrounded and an increased resistance established to the ease of operation of the same and a constant tendency to break. The terminal seats on the spindle never come in contact with the ends of the holder by reason of the fact that the cord will be attached to or 70 operate on such intermediate portion of said spindle that either extremity of the same will have become fully unwound before the inner portions of the said seats will have come into 75 contacting proximity to the ends of the holder, 80 and consequently the operation of the device will be effected without jar or abrupt vibration. When the cord extremities become 85 fully unwound, the point of inner limit of the same on the spindle will stand in direct transverse alignment to the eyes in the rim, and the length of cord between said inner limit on the spindle and the eye in either instance will operate as a resilient cushion in view of its 90 tense condition and obstruct any tendency 95 of the spindle to further project from the holder in the direction in which it has been moving without jar or irregular movement. The principal object sought in the improved construction of spinner is to give the spindle 100 a positive upward movement, and this will be particularly apparent in the forms having the cord secured to the spindle either by the eye therethrough or the surrounding groove feature, which is in contradistinction to the operation of spinners as heretofore produced, and to introduce the additional advantage of 105 reversibility of the device, so that either end of the spindle can be used to receive the top without requiring manual winding operations 110 to reset or prepare the device for subsequent similar operations. In this particular the device may be said to be automatic and will be found convenient in continuing a number of 115 actuations without delay.

In the operation of the improved device the plug end of the top is disposed in one of the terminal seats 6, with the arms 7 engaging the grooves 10. The holder is firmly grasped with one hand, and the cord extremity is operated by the other hand and drawn off and outwardly from the spindle and away from the said holder. This outward drawing of the cord will cause the spindle to rotate and simultaneously elevate, and the speed of rotation of the spindle will be imparted to the top, and the rapidity of rotation of the two intimately-related parts will depend exclusively on the quick or slower outward movement of the cord extremity. 125 When the spindle will have reached its full projection by reason of the cord extremity having been fully unwound from the same, there will be no shock or jar for reasons before explained, and the top continuing to 130 move or rotate will easily unseat itself by reason of the arms 7 and the grooves 10 having the

same spiral direction, and the top can thus be caused to fall on the ground or other surface desired while the holder is held stationary in the hand of the operator. The other end 5 of the spindle can then be turned uppermost for a similar operation, and the cord extremity corresponding thereto will be fully wound and ready for actuation without delay.

It is proposed to make the parts of the improved device of light material of a strong and durable nature and to ornament the same by plating or otherwise. The two forms of holders shown are so shaped and arranged that they may be easily grasped by the hands 15 of the operator without engaging any part of the spindle, and thereby avoid retarding the operation of the latter and the unwinding and winding of the cord.

Changes in the form, size, proportions, and 20 minor details may be resorted to without departing from the principle of the invention.

Having thus described the invention, what is claimed as new is—

1. A top-spinner having a holder, a top-engaging spindle mounted in the holder, and a flexible spindle-operating element reeled upon the spindle, the holder open at one side and having a guard at the opposite side parallel with and spaced from the spindle a distance equal to the thickness of the spindle-operating element and having contact with one point only of the coils of the latter.

2. A top-spinner having a holder, a spindle 35 slidingly mounted in the holder and having terminal top-engaging members for alternate use, and flexible spindle-rotating elements connected with the spindle and either coiled or reeled thereon as the spindle is turned by the uncoiling or unreeling of the other.

3. A top-spinner having a holder, a spindle slidingly mounted in the holder and having terminal top-engaging members for alternate use, and flexible spindle-rotating elements connected with the spindle and either coiled 45 or reeled thereon as the spindle is turned by the uncoiling or unreeling of the other, the holder having a guard at one side exclusively parallel with and spaced from the spindle a distance equal to the thickness of the 50 spindle-operating element and having contact with one point only of the coils of the latter.

4. The combination of a top, and an operating-spindle therefor, one of said devices having similarly-projecting spiral members and 55 the other grooves of a corresponding construction to receive said members.

5. A top-spinner comprising a holder, and a rotatable spindle having top-engaging seats at the opposite terminals thereof for reversible use.

6. A top-spinner comprising a holder having a yielding frictional bearing element at one side exclusively, a spindle longitudinally and rotatably movable therein and provided 65 with terminal seats to receive a top, and a cord regularly coiled on the spindle in loose contact with the frictional bearing element and having its opposite extremities extending through reverse portions of the holder near 70 opposite ends of the latter.

7. A top-spinner comprising a holder having a bearing element, a spindle longitudinally and rotatably movable therein and provided with terminal seats to receive a top, and 75 a cord regularly coiled on the spindle from an intermediate point outwardly and partially contacting with the bearing element, the opposite extremities of the cord extending through reverse portions of the holder near the opposite ends of the latter.

8. A top-spinner comprising a holder having a yielding bearing element, a spindle longitudinally and rotatably movable therein and provided with terminal seats to receive a 85 top, a cord regularly coiled on and secured to an intermediate portion of the spindle and partially contacting with the bearing element, the opposite extremities of the cord extending through reverse portions of the holder 90 near the opposite ends of the latter, the lengths of the cord between the point of securement on the spindle and the portions of the holder through which said cord extremities extend, when the latter are unwound, forming resili- 95 ent cushions for the spindle.

In testimony that I claim the foregoing as my own I have hereto affixed my signature in the presence of two witnesses.

ALFRED WHITE MORGAN.
